OPEN CENTER CONTROL VALVE FOR DOUBLE-ACTING MOTORS

Samuel G. Williams, Cape Vincent, N. Y., assignor to The New York Air Brake Company, a corporation of New Jersey

Application July 1, 1954, Serial No. 440,653

3 Claims. (Cl. 137—622)

This invention relates to control valves for double-acting fluid pressure motors, particularly hydraulic motors.

The invention provides a balanced open-center valve having three functional positions useful when a double-acting motor is to be controlled and hydraulic liquid is supplied by a constantly running pump. The three positions are a mid-position in which the pump is unloaded (discharge connected to inlet) and the motor is hydraulically locked (both motor ports blanked) and two end positions in which different ones of the two motor ports are connected to supply while the other motor port is connected to discharge, commonly to the sump from which the pump draws its supply.

Valves having these functional characteristics are known but as heretofore contrived are expensive to construct, and subject to troublesome leakage.

The invention affords a notably inexpensive construction on which a balanced sleeve valve surrounds a cylindrical seat. In this seat adequate ports are formed by simple drilling operations. The exhaust passage surrounds the valve sleeve so that any leakage passes to exhaust (i. e. to the sump) and is wholly internal to the valve.

The actuating stem which shifts the valve sleeve introduces a negligible unbalance and can be sealed very effectively, because a negligible pressure acts upon it.

A preferred embodiment offering all the above-enumerated advantages will now be described by reference to the accompanying drawing in which:

Fig. 1 is a view chiefly in axial section.

Fig. 2 is an elevation of the right hand end of the valve as positioned in Fig. 1.

Figs. 3-7 respectively are sections through the sleeve valve and its seat on the planes 3—3, 4—4, 5—5, 6—6, and 7—7 indicated in Fig. 1 and looking in the direction of the arrows.

Fig. 8 is a miniature diagram showing one way in which the valve may be connected between a constantly running pump and a double-acting piston motor.

All statements of direction refer to the valve positioned as in Figure 1. The hydraulic liquid is customarily an oil.

The housing for the valve comprises a head 11 and a cup shaped cap 12. The two are sealed together by a toric gasket 13 and are held together by four machine screws 14.

Projecting from the head 11 and completely enclosed by cap 12 is the valve seat 15 which takes the form of a solid right circular cylinder integral with head 11 and spaced from cap 12 both peripherally and at its left hand end. At its left hand end it carries a guide stem 16 for the valve actuator and this guide stem is ported axially and diametrically, as shown at 17, so that the actuator will not be oil-bound.

The valve element is a sleeve 18 axially slidable on seat 15, and having three internal annular grooves, a wide supply-groove 19 at mid-length and two relatively

2

narrow exhaust grooves 21 and 22 shown as symmetrically spaced on opposite sides of groove 19. Symmetrical spacing is not critical, as the location of valve ports is a function of the location of the coacting seat ports. 5 Through-ports 23, 24 lead through the sleeve 18 from grooves 21, 22 respectively.

A centering spring 25 biases the sleeve 18 from any position toward the open-center mid-position illustrated in Figure 1. Spring 25 is a coil compression spring which reacts between two rings 26 each slidable on sleeve 18. The rings 26 are dimensioned to engage two spaced internal shoulders 27 on cap 12 and body 11 respectively and two similarly spaced external shoulders 28 on valve sleeve 18. The shoulders 28 are constructed as snap rings seated in encircling grooves in the sleeve 18, a detail facilitating assembly. Observe that the shoulders 27 need not be removable since parts 11, 12 on which they are formed are separable.

An actuator 31 for valve sleeve 18 has a guideway 32 for stem 16 and works through a port in the end of cap 12. An O-ring 33 is used to resist leakage. The actuator 31 has a ported flange 34 which is seated in a circular recess in the left end of sleeve 18 and is there retained by a snap ring 35.

Thus sleeve 18 normally seeks the position shown in Figure 1 but may be moved a limited distance in either direction by shifting actuator 31. A connection 36 leads to the low pressure reservoir or sump so that the sleeve 18 is not subject to any significant hydraulic imbalance.

The construction above described makes it possible to form the seat ports by simple drilling operations and to keep the diameter of seat 15 to a reasonable minimum. Three longitudinal flow passages parallel with the axis are used. To conserve space and still have passages of substantial diameter, these are spaced at the corners of an equilateral triangle. They are all subject to the same maximum pressure, i. e., the head pressure delivered by the pump.

The longest of the three is the passage 37 for the left end ports 38 which are produced by cross drilling. (See Figure 4.) The shortest is passage 39 for the right end ports 41 also produced by cross-drilling, see Figure 6. The supply passage 42 has a length intermediate the lengths of passages 37 and 39 and supplies two sets of cross drilled ports, namely 43 which are motor supply ports (see Figure 5) and 44 which are the open center unloading ports, (see Figure 7).

Each of the passages 37, 39 and 42 has a radially extending connection 45, 46, 47 respectively. Plugs 48 (see Figures 1 and 2) are screwed into the ends of the passages 37, 39 and 42. This is because the passages are too closely spaced to permit convenient connection of pipes at the end of head 11.

As a basis for explanation, one system developing the utility of the valve is diagrammed in Figure 8. A sump S serves as a reservoir for hydraulic liquid, receives this from discharge connection 36 and delivers it to the inlet of pump P. The discharge of pump P is connected to the supply connection 47. The opposite ends of the double-acting piston motor M are connected respectively to connections 45 and 46. This is one of several common systems with which the valve may be used.

Operation

In the position of Figure 1 ports 38, 41 and 43 are blanked, but 42 is connected to exhaust via 44, 22, 24 and connection 36. This is the open-center path that unloads the constantly running pump P.

Both sets of motor ports 38 and 41 are blanked. Hence the connected motor M is hydraulically locked. Supply passage 42 is connected to exhaust connection 36 via ports 44, 22, 24, so the pump P is unloaded.

To operate the motor M in one or the other direction, valve sleeve 18 is moved in one or the other direction until groove 19 overlies one or the other set of motor ports 38 or 41. This occurs at one or the other limit of motion, as defined by collision of sleeve valve 18 with head 11 or the cap 12. At such time the set of ports 41 or 38 not in communication with groove 19 will communicate with exhaust groove 22 or 21 as the case may be. Hence a selected end of the motor M is connected to pump discharge and the other to pump suction.

The valve can be produced with a very small number of machining operations and all of these are simple and adapted to mass production. The only surfaces requiring high precision are the surface of seat 15 and the bore of sleeve 18. The grooves 19, 21 and 22 do not require precise machining and the ports and passages 23, 24, 37, 38, 39, 41, 42, 43, and 44 are produced by simple drilling operations. Economy is thus had without detriment to performance.

The valve 18 is balanced to all intents and purposes and the seal 33 can be simple, since port 36 is under no appreciable pressure. Such valve leakage as may occur is strictly internal. It will be small if the mating surfaces are reasonably well fitted because adequate port spacing is afforded.

The invention resides in the construction of the valve elements rather than in the function of the valve. The expedients used in the illustrated embodiment in mounting the centering spring and the actuator are subject to considerable variation.

I claim:

1. An open center balanced valve comprising a head having a projecting cylindrical valve seat; a cap attached to said head and enclosing said seat; a valve sleeve encircling said seat and shiftable axially thereon said sleeve having within its bore a supply-port recess substantially at mid-length and two exhaust-port recesses located be-

tween the supply-port recess and respective ends of the sleeve said exhaust port recesses each communicating with the space surrounding the sleeve; means affording a discharge connection to the space surrounding the sleeve and within the cap; and means affording seat ports and three distinct connections therefor, said means comprising three distinct parallel bores extending longitudinally from the head part-way through the cylindrical seat, of which one is a supply bore adapted for connection with pump discharge and communicating with two sets of cross-ports, a first set at approximately mid-length of the seat, and a second set positioned to communicate with an exhaust port recess in the sleeve when the latter is in mid-position, and the second and third are motor bores each adapted for connection with a corresponding motor space and each communicating with corresponding cross-ports, said cross-ports being at opposite sides of the first set of supply cross-ports, and positioned between the supply-port recess and a corresponding exhaust-port recess of the sleeve, when the sleeve is in its mid-position.

2. The combination defined in claim 1 in which the supply port recess and the two exhaust port recesses in the sleeve are annular grooves encircling the bore of the sleeve.

25 3. The combination defined in claim 1 in which the cross-ports include a passage drilled diametrically through the valve seat, said passage in each instance intersecting one of said longitudinal bores and passing between the other two longitudinal bores or the geometrical projection 30 of said longitudinal bores as the case may be.
